UNITED STATES PATENT OFFICE.

JOSEPH VIRZI, OF NEW YORK, N. Y.

SOUNDING-BOARD FOR MUSICAL INSTRUMENTS.

1,351,709.

Specification of Letters Patent. Patented Aug. 31, 1920.

Application filed February 12, 1920. Serial No. 358,165.

To all whom it may concern:

Be it known that I, JOSEPH VIRZI, a citizen of Italy, having declared my intention of becoming a citizen of the United States, and resident of New York city, borough of Manhattan, in the county and State of New York, have invented a new and Improved Sounding-Board for Musical Instruments, of which the following is a full, clear, and 10 exact description.

This invention relates to musical instruments, but has particular reference to sounding boards for such instruments as violins, violas, cellos, pianos or the like in which 15 there is ordinarily used a sounding board as a means amplifying the sound vibrations.

Among the objects of the invention is to provide an auxiliary sounding board arranged in spaced relation to the main sounding board of the instrument and having the periphery thereof disconnected from all other parts of the instrument.

Another object of the invention is to provide a new arrangement or correlation between the main and auxiliary sounding boards and the portion of the instrument over which the strings are stretched and commonly known as the bridge.

With the foregoing and other objects in 30 view the invention resides in the novel features of construction hereinafter more fully set forth and claimed, and illustrated in the accompanying drawings, in which

Figure 1 is a longitudinal central section 35 of an instrument of the violin type having my improvement attached thereto within the body.

Fig. 2 is a partial plan view and partial section on the line 2—2 of Fig. 1 showing 40 the same invention.

Fig. 3 is a vertical transverse section on the line 3—3 of Fig. 2.

Fig. 4 is a vertical longitudinal section on the line 4—4 of Fig. 3.

Fig. 5 is a plan view of a modified form 45 of auxiliary sounding board.

Fig. 6 is a fragmentary longitudinal section of a violin indicating the form of sounding board such as shown in Fig. 5 50 attached thereto.

Fig. 7 is a vertical transverse section on the line 7—7 of Fig. 6.

Fig. 8 is a longitudinal central section of a further modification.

Fig. 9 is a vertical transverse section of 55 the same on the line 9—9.

Fig. 10 is a detail sectional view indicating a slight variation from the structure of Figs. 8 and 9.

Fig. 11 is a rear elevation of a piano indicating my improvement.

Fig. 12 is a vertical sectional view of the same on the line 12—12.

Figs. 13 and 14 are horizontal sections on the corresponding lines of Fig. 11. 65

Referring now more specifically to the drawings, I indicate in Fig. 1 a sounding board 15 constituting the top portion of the body of such instrument. As usual I indicate a bass bar 16 secured against the inner 70 surface of the sounding board 15 for strengthening and reinforcing this portion of the instrument. 17 indicates the usual bridge over which the strings 18 are stretched from the tail-piece 19. As shown in Figs. 1 to 4, my improved free sounding board is shown at 20, the same being supported upon the main sounding board 15 by means of two supports 21. These elements are shown best in Fig. 4, each comprising a sort of pin or 75 short post fixed by any suitable means to the under surface of the sounding board 15 and also connected to the upper surface or portion of the auxiliary sounding board 20. The free sounding boards and their connections may be of any suitable material. 80 These connections may be effected by glue, metal fasteners or any other convenient means, and such fastening may be made more secure by employment of a tenon projecting into corresponding mortises in the several parts. Two of these supports 21 are sufficient for holding the sounding board 20 in spaced relation to the main sounding board, the same being shaped so as to conform 85 substantially to the convexity of the sounding board 15 and substantially parallel thereto. One of the principal features of the present improvement is to attach the auxiliary sounding board to the main sounding board by means in alignment with the bridge.

In Figs. 5 to 7 the free sounding board 20^a having more transverse convexity than in former Figs. 1 and 3, the central convex 100 crown portion thereof 22 is adapted to bear directly against the main sounding board 15 beneath the bridge. The fastening means

may be dowel pins, but preferably it is glue. As shown best in Fig. 7 the lateral edge portions of the sounding board 20^a are free from the main sounding board as well as from the bass bar 16.

In my extensive experimenting and experience in the manufacture of musical instruments I have found that the particular manner or place of attaching the free sound-
10 ing board is not essential and hence as a further variation from the forms and means for attachment above set forth, the sounding board 20^b may be secured directly to that portion of the bass bar 16 that lies just within
15 in the bridge 17, leaving the end portions as well as the lateral portions free from all other parts. In Fig. 10 the attachment between the sounding board 20^b and the bass bar includes a dowel 23.

20 Referring now to the adaptation of my invention to a piano having any usual or approved sounding board 25, to which is fixed a bridge 26, I show my improvement in the nature of an auxiliary sounding board 20^c
25 having a general curvature corresponding to the compound curvature of the bridge 26 but located on the opposite side of the sounding board 25 from the bridge 26. The two sounding boards are spaced from each other
30 and the spacing means comprises a series of supports 21^a following the course of the bridge 26, so that the main connecting means between the sounding boards may be said to be in alinement with the bridge. The supports 21^a are not only spacers between the
35 two sounding boards but constitute the main

supports for the auxiliary sounding board. The attachment may be made effective by any suitable means such as glue or additional dowels 23^a or the like. These dowels 40 23^a are shown as extending all the way through the supports and main sounding board and into or through the bridge and the auxiliary sounding board. As will be appreciated from Fig. 11 the main supports 45 or posts 21^a for the auxiliary sounding board follow closely the longitudinal median line from one end of the sounding board to the other. These posts may be the only supports for this member, but it may be preferable to employ additional posts 21^b along the side portions of the free sounding board but preferably not at the extreme edges thereof, the edges being left free in all forms 50 of the invention.

55 I claim:

1. In a musical instrument, the combination with a sounding board and a bridge on one side thereof, of an auxiliary sounding board on the opposite side of the main 60 sounding board from the bridge, and means extending between the sounding boards to support the auxiliary sounding board leaving the periphery of the auxiliary sounding board free, said supporting means being in 65 alinement with the bridge.

2. A musical instrument of the nature set forth in claim 1 in which the supporting means is in the nature of short posts with their ends fastened to both sounding boards. 70

JOSEPH VIRZI.
